DESIGN FOR A COMMUNION CUP TRAY

Allan P. Lindblad, Winchester, Mass.

Application November 13, 1943, Serial No. 111,686

Term of patent 7 years

(Cl. D44—10)

To all whom it may concern:

Be it known that I, Allan P. Lindblad, a citizen of the United States, residing at Winchester, in county of Middlesex and Commonwealth of Massachusetts, have invented a new, original, and ornamental Design for Communion Cup Trays, of which the following is a specification, reference being had to the accompanying drawing, forming a part thereof.

Fig. 1 is a perspective view of the communion cup tray, showing my design, the parts thereof being shown separated from one another;

Fig. 2 is a cross-sectional view of the communion cup tray showing the parts thereof in vertical alinement with the cup tray proper raised above the base and the cover raised above the tray proper;

Fig. 3 is a perspective view showing the communion cup tray with the parts in assembled position.

I claim:

The ornamental design for a communion cup tray, substantially as shown and described.

ALLAN P. LINDBLAD.
